Application December 17, 1938, Serial No. 246,261

13 Claims. (Cl. 209—170)

This invention relates to the concentration of ores, and has for its principal object the provision of a new and improved apparatus for the concentration of ores by flotation.

5 Customary methods of concentrating ores by flotation involve the fundamental feature of producing a froth possessing selective attraction or preference for the metalliferous particles of an ore pulp in contradistinction to the gangue particles thereof. For the formation of the froth, air or other appropriate gas is essential and commonly such air is provided by agitation or aeration or by a combination of aeration and agitation of the ore pulp, or, as described in my
 10 15 Patent No. 1,599,561, dated September 14, 1926, by causing an ore pulp containing an appropriate flotation agent to impinge, in the presence of air or other appropriate gas, against a baffling surface or the surface of a body of the pulp with sufficient violence effectively to break up the ore pulp streams and thereby form a mineral-bearing froth.

The mineral-bearing froth formed as described in my above-mentioned patent is trapped beneath the surface of the main body of the ore pulp and is recovered from a relatively quiescent zone of the main body of ore pulp. Preferably the ore pulp is circulated within an appropriate receptacle, in the course of which circulation the ore pulp is elevated to a height above the normal operating ore pulp level in the receptacle and discharged back into the receptacle where it is intercepted by the surface of the ore pulp or by an appropriately positioned baffle with sufficient violence to form a mineral-bearing froth.

35 The apparatus of the present invention is especially adapted for the practice of a method such as that described in my above-mentioned patent. This apparatus comprises an elongated receptacle adapted to contain ore pulp and divided into a plurality of cells, in each of which is provided appropriate means for effecting a circulation of ore pulp in a path substantially at right angles to the direction of flow of the ore pulp through the vessel. The circulation of the ore pulp in each cell of the apparatus is carried out in the manner which characterizes my above-described method of flotation, that is, with the elevation of the ore pulp, preferably pneumatically, to a height above the normal operating ore pulp level in the receptacle, then the re-direction of this ore pulp outwardly and downwardly against a baffling surface and against the ore pulp not so elevated with sufficient violence to form a mineral-bearing froth.

55 The elongated pulp receptacle of the invention is divided into a plurality of intercommunicating cells by one or more divider plates mounted transversely of the receptacle. In my preferred apparatus, at least two spaced vertical baffles

are mounted in each cell extending longitudinally thereof. The vertical baffles extend downwardly from a point slightly above the normal pulp level in the cell almost to the bottom of the cell. An elongated air header is positioned in each cell between the vertical baffles and extends downwardly into the cell to point substantially below the normal pulp level in the receptacle.

5 One of the features of my improved apparatus is the provision of what I term a "stream-lined" path for the circulation of the ore pulp, so as to avoid any abrupt changes of direction of flow of the pulp. Where such abrupt changes occur, or where the pulp cell is so shaped that eddy currents are set up, there is a tendency for the 10 solids to settle out of the pulp and deposit in the bottom part of the cells. Such settling out of solids causes irregularities in, or blocks, the free circulation of the pulp, resulting eventually in 15 unsatisfactory operation of the cell.

This "stream-lined" path preferably is contoured and dimensioned as regards cross section area in a manner gradually but not abruptly to increase the velocity of the pulp at those places where there would otherwise be a tendency for 20 the solids to settle out and thus block the free flow of and upset the even distribution of sands 25 in the pulp.

As an example of such "stream-lining" of the 30 path of pulp circulation in the new apparatus, the junction between the bottom wall and the upwardly sloping side walls of the pulp receptacle are curved concavely from within the receptacle, and the lower edges of the vertical baffles, which are positioned in the receptacle substantially 35 vertically above said curved junctions, are curved correspondingly therewith to provide a passage free of abrupt changes in direction for the flow of pulp from the spaces between the vertical baffles and the side walls of the receptacle to 40 the space between the baffles.

Another feature of my new apparatus is the provision made to insure even distribution of the air introduced into the pulp.

In machines of the type to which the invention relates, compressed air is discharged into the pulp at or near the lowest point of the cell, and the resulting mixture of air and pulp rises in an air-lift column whose intake is open substantially throughout the length of the cell bottom. Heretofore in similar machines (such as the so-called "Forester" machine) the air has been discharged from pipe openings spaced so far apart (about 7" to 9" center to center) that comparatively dead spaces of pulp are left 50 between the air pipe openings, and consequently the efficiency of the cell is impaired because the mixing of bubbles of air with the pulp is not uniform. Uneven mixing of air and pulp results in 55 an uneven lifting force in the air-lift, uneven 60

froth flotation of the mineral contents of the pulp, and settling out of solids in those spaces between the air pipe openings where the pulp is less aerated and agitated.

- 5 When the pulp contains relatively coarse sands, or when the pulp is one from which the sands settle out rapidly, any opportunity for solids to settle out in the machine results in gradually building up sands in the pulp passageways and 10 thus choking operation of the machine. This necessitates special hand or excessive high-pressure air agitation to free the chokes, or, alternatively, a very much larger amount of compressed air must be used continuously. Excess 15 air thus used not only wastes power, but also causes a too rapid overflow of froth, making close regulation of the richness of the froth impossible.

In my machine the compressed air is discharged 20 from the header through pipe openings spaced very closely together. In order to secure adequately close spacing, the pipes are made small in diameter, and they are made short in length to reduce power losses due to friction, to increase 25 their rigidity and to reduce the cost of renewals. In order to employ the short pipes effectively, the intake ends are fixed into an air header positioned considerably below the pulp level instead of, as in other machines, above this level.

- 30 A further provision also has been made to insure uniform aeration of the pulp. In those machines in which unequal amounts of air are introduced into the pulp from each pipe opening, there is a tendency for pulp of greater density to 35 accumulate at the openings of the pipes discharging the lesser amount of air, due to the reduced agitation and pulp flow in the vicinity of these pipe openings. This increases settling action at, and under, such openings, resulting 40 eventually in the solids settling out around the openings and choking the discharge of air altogether.

In my machine equal distribution of air from 45 each pipe opening is induced by throttling the air discharged from each pipe. This is accomplished by reducing the area of the opening into the pipe at the intake end, so that the drop in air pressure due to the restricted intake is sufficient to prevent irregularities in pulp density at the 50 discharge end of the pipes from affecting to a substantial extent the equality of flow of air from the pipes. The restriction is made at the intake end so that pulp finding its way into the air pipes may freely flow out again.

- 55 The prevention of sand chokes over considerable areas at the bottom of the air lift is further assisted by varying the depths to which the discharge openings of the air pipes extend into the pulp. In my preferred apparatus air pipes discharge openings are arranged at two or more depths by employing air pipes of different lengths, and the depths of the discharge openings in the pulp are staggered in a manner such that the pipe openings deepest in the ore pulp have adjacent to them on either side pipe openings at a lesser depth. To this end, alternate air discharge pipes mounted in the header are made longer than and extend downwardly into the pulp to a point below the discharge ends of the intervening 60 air pipes.

When in operation of the cell the quantity of compressed air supplied to the cell is reduced in order to reduce the overflow of froth, the throttling action of the pipe restrictions referred to 65 above becomes less effective, but the uniform dis-

tribution of air is still maintained by the effect of the alternate comparatively deep and shallow pipe openings. Should the flow of air from the deep pipe openings become substantially reduced or fail, the flow of air from the flanking less deep pipe openings will be increased, and thus any tendency for chokes to form at the bottom of the air-lift in irregular areas will either be prevented altogether, or be restricted to a very small area, i. e. the area between any two air pipes. 5

A further feature of my new machine is the novel arrangement of means for collecting the submerged froth bubbles in the quiescent part of the pulp and the rapid discharge of the froth without moving mechanism, these means comprising baffles arranged in the form of an inverted-funnel-shaped section into which the froth bubbles rise. The small end of the funnel-shaped section forms a narrow vertical columnar section at the top of which the froth overflows. 10 The height of the overflow of this narrow column is made adjustable so that the rate of froth overflow, which rate determines the richness in mineral content of the concentrated ore product of the cell, can be regulated. The narrow vertical 15 froth column is made sufficiently high, in any given case, to provide enough time, as the bubbles rise therethrough, for the froth to clean itself of such gangue material as may be inadvertently trapped in the rising bubbles. Increasing the 20 height of this column reduces the velocity of upward travel of the bubbles and enables more thorough cleaning, with slower overflow, of froth. 25

The large area of intake opening provided by the inverted - funnel - shaped froth - collecting 30 means assures that the maximum number of mineral-bearing bubbles are caught and forced to travel upwardly into the froth-cleaning column. 35

Still another novel feature of my preferred machine is the provision of substantially laterally positioned guide vanes or baffles interposed in the path of circulation of the ore pulp in the cell and curved to impart a component of forward motion to the circulating pulp, thereby to insure flow of pulp longitudinally through the cells in 40 series. These baffles thus provide means for propelling the pulp longitudinally through the long length of the receptacle making it unnecessary to give the bottom of the receptacle a slope in the direction of flow of pulp and making it possible to operate machines of indefinite length on 45 one level floor.

The foregoing and other novel features of the invention will be better understood from the following description taken in conjunction with 50 the accompanying drawings, in which—

Fig. 1 is a cross-section, taken substantially along line 1—1 of Fig. 2, through a flotation cell embodying features of the invention;

Fig. 2 is a longitudinal section taken substantially along line 2—2 of Fig. 1;

Fig. 3 is a cross-section through a pulp receptacle showing a divider plate in elevation;

Fig. 4 is a plan view of an air-lift assembly 55 employed in the new cell;

Fig. 5 is a cross-section through the air-lift taken substantially along line 5—5 of Fig. 4;

Fig. 6 is an enlarged cross-section through the lower end of the air header;

Fig. 7 is a longitudinal section through one end 70 of a pulp receptacle showing details of construction in one cell; and

Fig. 8 is a cross-section through a plant installation of the new apparatus.

The apparatus of the invention comprises an 75

elongated pulp receptacle 10 (Fig. 7) divided into a plurality of cells 11 by divider plates 12. The divider plates 12 extend from the top of the receptacle downwardly to a point somewhat below the normal level of pulp in the cell (indicated approximately by the broken line 13), leaving openings 14 of large area for communication between the several cells below the normal level 13 of pulp in the cell.

10 The receptacle 10 (Fig. 1) comprises a bottom wall 15 and side walls 16, the lower portions of which slope upwardly and outwardly from the bottom walls. Mid-portions 17 of the side walls are arranged substantially vertically, and above these vertical portions the side walls slope inwardly and upwardly as at 18, and thence vertically as at 19.

The divider plates 12 which divide the receptacle into a plurality of intercommunicating cells 20 are provided on each side with a pair of spaced guide brackets 20 between which an air-lift assembly is received. The air-lift assembly comprises a pair of spaced, vertically positioned baffles 21 extending from a point slightly above the normal level 13 of pulp in the cell downwardly to a point adjacent the bottom of the cell. An air header is positioned in the space between the vertical baffles 21 and extends from a point above the normal level of pulp in the cell downwardly into the pulp to a point substantially below the normal pulp level.

The air header comprises an elongated, relatively thin box-like structure having spaced, relatively deep side plates 23 held in proper spaced relation with respect to one another by spacers 24, and closed by a bottom closure 25, end closures 26, and a cover 27. The end closures 26 of the air header extend laterally outwardly substantially beyond the side plates 23 thereof 40 and are formed with flanges 28. The vertical baffles 21 are riveted or otherwise fastened to and supported by the flanges 28 of the header end closures.

The upper portions of the end closures extend laterally outwardly beyond even the vertical baffles 21 and are provided with flanges 29 for reception between the guide brackets 20 mounted on the divider plates 12. Since in the preferred form of the apparatus the flanges 29 extend to a point below the upper edges of the vertical baffles 21 (in order to provide ample guiding and supporting area for the upper portion of the air-lift assembly), brackets 30 are provided for supporting the upper portions of the vertical baffles 21.

The end closures 26 of the air header also extend downwardly below the side plates 23 about to the lower edges of the vertical baffles 21, and have their own lower edges notched to provide a recess in the form of an inverted V. A flange 31 is welded or otherwise secured to the end plates 26 about the edges of the inverted V recess, which flanges rest on chairs 32 riveted or otherwise secured to the bottom wall 15 of the receptacle with the air-lift assembly positioned in the cell as shown in Figure 1. The weight of the air-lift assembly is carried by the end closures resting on the chair 32, and it is held in an upright position by the flanges 29 received between the guide brackets 20.

The upper portions 33 of the side plates 23 of the air header are curved outwardly and downwardly to provide curved deflecting baffles extending over and beyond the upper edges of the vertical baffles 21 and are supported at their outer

curved edges by outwardly extending projections 34 of the end closures 26.

The cover member 27 of the air header preferably comprises a pair of channel members 35 (which form a shallow frame for the header assembly) to which the outwardly curved portions 33 of the header side plates are secured. A flat cover plate 36 spans and is secured to the channel members 35.

Means in the form of a valve 37 connected to the cover plate 36 provide for introducing air under pressure into the interior of the header. Eye-bolts 38 are secured to the channel members 35 to provide convenient means for removing the air-lift assembly from the cell.

The bottom closure 25 of the air header 22 is preferably a strip, of shallow V cross-section, suitably secured to the side plates 23 at their lower edges, as by welding. A large number of downwardly-projecting air discharge pipes or conduits 39 are threaded into suitably tapped holes arranged in two parallel longitudinal rows in the closure 25.

For purposes of collecting froth formed in the cell a pair of longitudinal vertical baffles 40, each having its lower edge portion turned inwardly to form a lip 41, are riveted or otherwise suitably secured to brackets 42 mounted on the divider plates 12 near the outer edges thereof. The baffle 40 is vertically positioned substantially parallel to the vertical baffle 21 of the air-lift assembly between this baffle and the vertical side wall 19 of the receptacle. The inclined lip 41 at the lower edge of the baffle 40 cooperates with the inwardly sloping portion 18 of the side wall of the receptacle to form inverted-funnel-shaped collecting means for the froth, and the vertical baffle 40 itself cooperates with the upper vertical portion 19 of the side wall of the receptacle to form a froth collecting and cleaning column. The effective height of this froth collecting and cleaning column is made adjustable by the provision of a gate or weir 43 of adjustable height. The gate 43 comprises one or more plates 44 removably mounted in brackets 45 secured to the outer edges of the divider plates 12. The effective height of the froth collecting column between the gate 43 and the vertical baffle 40 is determined by the height of the gate or weir 43, so that by employing plates 44 of greater or lesser width, or by employing more or less plates 44 of the same width, the effective height of the froth collecting column may be varied at will. Splash boards 46 are mounted below the gate 43 to catch froth overflowing the gate from the froth collecting column.

As an alternative to the froth collecting means specifically described above, I have investigated the possibility of omitting the inwardly sloping portion 18 of the side wall of the receptacle and instead carrying the side wall vertically upwardly from the vertical mid-portion 17 thereof, with the vertical baffle 40 shifted outwardly in correspondence with such outward shift of the side wall of the receptacle, and with corresponding lengthening of the lip 41. Experiments prove the structure so modified to be substantially less efficient than the structure shown in the drawings and described in conjunction therewith, however.

With the air-lift assembly in position as described in a cell of the receptacle, and with the cell filled approximately to its normal level with a suitable ore pulp containing appropriate flotation reagents, the apparatus operates substantially as follows: Air under pressure is introduced into the header 22 through the valve 37

and is discharged from the header through the discharge pipes 39. The air so discharged rises upwardly through the pulp, and by air-lift action induces upward circulation of the pulp, in the spaces between the side plates 23 of the header and the vertical baffles 21. The pulp attains considerable upward velocity as a result of the action of the air-lift, and upon ascending above the upper edges of the vertical baffles 21 is deflected outwardly and downwardly by the curved portions 33 of the header side plates (which in effect are deflecting baffles) against the surface of the pulp lying outside the air-lift and against the vertical baffles 40. A considerable amount of air is thus entrapped in the pulp with the attendant formation of a mineral bearing froth. The froth so formed is swept below the normal level of the pulp and into the relatively quiescent body of pulp underlying the lips 41 of the baffles 40. In this relatively quiescent body of pulp the froth rises and is collected in the funnel-shaped passage provided by the lip 41 and in inwardly sloping section 18 of the side wall of the receptacle, whereby it is directed into the vertical froth collecting column defined by the upper vertical sections 19 of the side walls of the receptacle and the baffles 40. The froth ascends this collecting column to a height determined by the height of the gate 43 and spills over the top thereof to the splash board 46, from which it flows or is washed into suitable collecting launders.

As pointed out in my above-mentioned patent, the richness of the froth, that is, the degree to which it is free from gangue particles, is determined by the height of the gate 43. The higher the gate the greater is the length of time required for the froth to ascend the froth column, and the greater, in consequence, is the opportunity for gangue particles to break loose from the froth and fall back into the main body of the pulp. In producing concentrates, the top of the gate 43 will extend almost to the top of the cell, whereas in producing middlings the upper edge of the gate 43 ordinarily will be considerably below the upper edge of the receptacle and may not be much above the splash board 46.

The ore pulp lying outside the vertical baffles 21 and below the froth formed and collected as described above responds to the action of the air lift by circulating downwardly toward the bottom of the receptacle, where it passes under the vertical baffles 21 and into position for upward circulation through the air-lift. In order to provide a path of pulp circulation substantially free of abrupt changes in direction, the junctions 47 between the horizontal bottom wall 50 of the pulp receptacle and the side walls sloping upwardly and outwardly therefrom are curved concavely from within the receptacle. The lower edge portions 48 of the vertical baffles 21 (which are proximate to but overlie the junctions 47) are bent outwardly and upwardly with a degree of curvature corresponding to that of the curved junctions 47. A curved passage 49 free of abrupt changes in direction thus is provided for the flow of pulp from outside the vertical baffles 21 into the space between them. The extreme edge portions 50 of the vertical baffles 21 lying beyond the curved portions 48 thereof, are bent inwardly toward the vertical portions of the baffles and provide, in conjunction with the outwardly sloping side walls 16 of the receptacle, a funnel-shaped section for directing pulp easily into the curved passages 49. The curved passages 49 and the funnel-shaped approaches thereto provide a minimum of resistance to the passage of pulp from the spaces out-

side the vertical baffles 21 to the space between them, and in consequence reduce materially the power required to operate the air-lift and maintain adequate pulp circulation.

Some importance attaches to the depth of the passages 49. The precise depth of the passages will vary somewhat depending on the conditions under which the cell is operating, but in any event the cross-sectional area of the passage (taken, of course, longitudinally of the cell) should be small in proportion to the cross-sectional area of the cell at points above the passage 49. In operation of the cell heavy sands tend to collect at the bottom and by making the cross-sectional area of the passages 49 relatively small the velocity of the circulating pulp passing through these passages is made relatively high; the tendency of heavy sands to settle thus is minimized.

Further to relieve the tendency of heavy sands to settle and clog or choke the machines, the pipes or conduits 39 through which air is discharged from the header 22 into the pulp are so constructed and arranged as to provide for uniform and even distribution of the air introduced into the pulp. To this end the conduits 39 (Fig. 6) are provided with intake openings 51 of reduced area where they are fitted in to the bottom closure 25 of the air header. Such reduction in the area of the intake opening 51 may be provided by bending the intake end of the conduits 39 inwardly (as shown in the drawing) or by otherwise partially plugging the intake end of these conduits. By thus reducing the intake-opening area of the conduits 39, discharge of air from the header is throttled somewhat so that accumulation of heavy sands in the vicinity of any discharge conduit or conduits does not materially affect the volume of air discharged therefrom. Such restriction in the conduits thus in effect anticipates accumulation of heavy sands, and prevents such accumulation, should it occur, from being the primary cause of throttling and bringing about a reduction in the amount of air introduced into the pulp. More uniform distribution of air than has heretofore been possible through pulp in which sands may not be uniformly distributed thus is assured. The restriction 51 in the conduit 39 preferably is provided as shown at the intake end in order that sands working into the interior of the conduit may freely be discharged therefrom.

Further provision for uniform distribution of air through the pulp is made by spacing the short discharge conduits 39 very closely together (Fig. 2) using, for this reason, pipes of small diameter and making them short in length so that they will possess desirable rigidity. Further provision for uniform distribution of air into the pulp is made by employing discharge pipes projecting various depths into the pulp. Thus alternate pipes 39a are relatively long and extend relatively deeply into the pulp. Flanking these relatively long pipes 39a are relatively short pipes 39b and 39c which project less deeply into the pulp. If desired, the relatively short pipes 39b and 39c may be all of the same length, thus providing for discharge of air at two depths in the pulp, but in my preferred apparatus one set of pipes 39b is made of intermediate length and another 39c is of still shorter length, so that discharge openings 60 are provided at three different depths in the pulp. By thus providing for introduction of air into the pulp at a plurality of depths, improved uniformity of air distribution through the pulp is achieved, and heavy accumulation of sands at the 65 70 75 80 85 90 95 100

discharge openings of the deepest pipes does not sufficiently impede the discharge of air to reduce materially the total volume of air introduced into the pulp.

5 As pointed out above, the cells described from individual units of which a considerable number are arranged in series throughout the length of the pulp receptacle 10. Ore pulp to be treated is introduced into a feed chamber 53 (Fig. 7) at 10 one end of the receptacle and passes thence through the cells in series to a discharge chamber (not shown) at the other end of the receptacle. In order to assure movement of the pulp longitudinally through the receptacle, a plurality 15 of laterally-arranged propelling baffles 54 are riveted or otherwise secured to the vertical baffles 21 of the air-lift assembly. These laterally arranged baffles are curved concavely from above and mounted in a manner such that a component of 20 forward motion is imparted to pulp moving downwardly in the space between the vertical baffles 21 and the side walls of the receptacle. Thus positive longitudinal propulsion of pulp through the cells in series is achieved, utilizing for this 25 purpose the force provided by the air-lift, and avoiding the customary expedient of inclining the bottom wall of the pulp receptacle to secure forward flow of pulp. Provision of the propelling baffles 54 makes it possible to operate cells of indefinite length on a level floor.

30 The laterally arranged baffles 54 serve another purpose in that they arrest downward movement of circulating pulp in which froth has been entrapped, and so enhance the opportunity of the 35 froth bubbles to separate from the pulp and rise upwardly in the zone of relative quiescence beneath the froth collecting lip 41.

The number of propelling baffles 54 required in any given installation, as well as their exact 40 curvature, is best established by trial, and once ascertained does not usually require alteration thereafter. To a considerable extent, correction for excessive forward propulsion of the pulp by the baffles 54 is automatically provided for by a 45 reverse flow of the pulp through the lower half of the receptacle, made possible by the very large openings between the cells below the divider plates 12.

50 Withdrawal of pulp that has traveled the length of the receptacle is made from the discharge chamber (not shown) at the end thereof through the agency of any suitable pulp-level regulator. A satisfactory pulp-level regulator is a standard low pressure air-lift which elevates the pulp from 55 the bottom of the discharge chamber and over the top thereof. The supply of air to the discharge air-lift in such a regulator is controlled by a float resting on the surface of the pulp in the discharge chamber. Any change in the pulp 60 level above or below the level to be maintained elevates or lowers the float to increase or decrease the supply of air to the discharge air-lift, and hence to increase or decrease the volume of tailings pumped from the chamber.

65 The air-lift assembly of the new apparatus as described above is removable as a unit from the cell for purposes of cleaning or repair. Preparatory to such removal, flexible air lines 55 (Figs. 7 and 8) are connected to valved inlets 56 provided 70 in the cover plate 36 of the air header. High pressure air from an air line 57 is admitted to the header 22 by opening the necessary valves, and the primary source of air to the header 22 from a main air line 58 is cut off by closing the 75 valve 37 mounted on the header and another

valve 59 in the branch conduit 60 through which air passes from the main air line to the header. A flexible section 61 in the branch line between the valves 59 and 37 is removed, and the entire air lift assembly is removed bodily from the cell by 5 a crane attaching to the eye-bolts 38.

The high pressure air supplied to the header from the line 57 serves to prevent the header from filling with pulp after closure of the valve 37 on the header and disconnection of the flexible section 61 of the main air supply line. The lines 55, being flexible, do not interfere with removal of the header from the cell, and after such removal may be disconnected.

10 It is apparent from the foregoing description 15 of my new apparatus that each cell is in effect a pair of independently operable half cells. If desired, operation of either half of the cell may be discontinued by closing the air discharge conduits 39 in the row along that half of the cell 20 which it is desired to close down. Moreover, the two halves of the cell may be made substantially completely independent in their operation by suitably closing the space between the bottom wall 25 of the air header between the two rows of 25 discharge pipes 39 therein and the bottom wall 15 of the receptacle. Such operation of only half of the cell or independent operation of both halves may be desirable in small installations, but in general operation of both halves of the 30 cell as described above is preferable.

I claim:

1. Apparatus for concentrating ores by flotation comprising an elongated receptacle adapted to contain ore pulp, divider plates mounted 35 transversely of the receptacle dividing the receptacle into a plurality of intercommunicating cells, a vertically disposed baffle mounted in the cell and extending from a point slightly above the normal pulp level in the cell to a point adjacent the bottom of the receptacle, and a second vertically disposed baffle arranged substantially parallel to said first-mentioned baffle between said first-mentioned baffle and a side wall of the receptacle and extending upwardly from 40 a point slightly below the normal pulp level in the cell, said second baffle having a lip at its lower end turned inwardly at an angle to the vertical toward said first-mentioned baffle, said 45 lip serving to assist in collection of froth formed 50 in the space between said two baffles.

2. Apparatus for concentrating ores by flotation comprising an elongated receptacle adapted to contain ore pulp, divider plates mounted transversely of the receptacle and extending from 55 a point above the normal level of pulp in the receptacle to a point therebelow but above the bottom of the receptacle, whereby the receptacle is divided into a plurality of cells communicating with each other adjacent the bottom of the 60 receptacle, means for inducing circulation of ore pulp within each cell in a direction substantially at right angles to the direction of flow of the ore pulp through the receptacle, and laterally positioned baffles interposed in the path of pulp 65 circulation in each cell and arranged to impart forward motion to the circulating pulp as said pulp circulates downwardly below the bottoms of the divider plates to insure flow of pulp longitudinally through the cells in series.

3. Apparatus for concentrating ores by flotation comprising an elongated receptacle adapted to contain ore pulp, divider plates mounted transversely of the receptacle and extending from a point above the normal level of pulp in the re- 75

- ceptacle to a point therebelow but above the bottom of the receptacle, whereby the receptacle is divided into a plurality of cells communicating with each other adjacent the bottom of the receptacle, pneumatic means for inducing circulation of ore pulp in each cell in a direction at right angles to the flow of pulp through the cells, and a plurality of laterally positioned baffles interposed in the path of the circulating pulp in each cell and curved to impart a component of forward motion to the circulating pulp as said pulp circulates downwardly below the bottoms of the divider plates to insure flow of pulp longitudinally through the cells in series.
15. 4. Apparatus for concentrating ores by flotation comprising an elongated receptacle adapted to contain ore pulp, divider plates mounted transversely of the receptacle dividing the receptacle into a plurality of intercommunicating cells, a pair of spaced, vertically disposed baffles mounted in each cell longitudinally of the receptacle, means for circulating pulp upwardly in the space between said baffles and downwardly in the spaces between each of said baffles and the side walls of the receptacle, and laterally arranged baffles mounted in the spaces between said vertical baffles and the side walls of the receptacle and curved concavely from above in a manner to impart a component of forward motion to pulp moving downwardly in said spaces.
5. In a flotation cell of the character described, a receptacle adapted to contain ore pulp, a pair of spaced, vertical baffles mounted in said receptacle, an elongated air header of relatively large cross sectional area mounted in the space between said baffles and extending to a point substantially below the normal level of pulp in the cell, and a plurality of short, closely spaced air discharge conduits of small diameter to permit close spacing mounted in the lower portion of said header and extending downwardly therefrom to a point adjacent the bottom of the receptacle.
6. An air header for use in flotation apparatus of the character described comprising a thin box-like structure of relatively large cross section area having spaced, substantially parallel side walls, end walls, bottom wall and cover, means for introducing air under pressure into said header, and a row of short, closely spaced air discharge conduits of small diameter to permit close spacing communicating with the interior of said header through the bottom wall thereof and extending downwardly therefrom.
55. 7. An air header for use in flotation apparatus of the character described comprising a thin box-like structure having spaced, substantially parallel side walls, end walls, bottom wall and cover, means for introducing air under pressure into said header, and a row of small, closely spaced air discharge conduits communicating with the interior of said header through the bottom wall thereof and extending downwardly therefrom, said air discharge conduits having restricted intake openings adjacent their points of communication with the interior of the header.
8. An air header for use in flotation apparatus of the character described comprising a thin box-like structure having spaced, substantially parallel side walls, end walls, bottom wall and cover,
- means for introducing air under pressure into said header, and a row of small, closely spaced air discharge conduits communicating with the interior of said header through the bottom wall thereof and extending downwardly therefrom, alternate air discharge conduits being longer than and extending downwardly to a point below the ends of the intervening air discharge conduits.
9. An air header for use in flotation apparatus of the character described comprising a pair of spaced side wall plates, and end, bottom and top closure members enclosing the space between said side wall plates, the upper edge portion of said side wall plates being curved outwardly and downwardly.
10. An air header for use in a flotation apparatus of the character described comprising a relatively shallow frame, a cover plate over said frame, a pair of relatively deep, relatively closely spaced side wall plates mounted substantially parallel to each other and curved outwardly and downwardly at their upper edge portions, said side wall plates being secured adjacent their upper curved edges to said frame, and end and bottom closures enclosing the space between said side wall plates.
11. An air lift assembly for use in flotation apparatus of the character described, comprising spaced, substantially parallel air header side plates, a bottom closure and a cover secured to said side plates adjacent the upper and lower edges thereof, end closures secured to said side plates at each end thereof and projecting laterally a substantial distance beyond the outer surfaces of said side plates, and baffle plates secured to said end closures adjacent their outer edges and supported thereby in spaced, substantially parallel relation with the header side plates.
12. An air lift assembly for use in flotation apparatus of the character described, comprising spaced substantially parallel air header side plates, a bottom closure and a cover secured to said side plates adjacent the upper and lower edges thereof and projecting laterally a substantial distance beyond the outer surfaces of said side plates, baffle plates secured to said end closures adjacent their outer edges and supported thereby in spaced, substantially parallel relation with the header side plates, and substantially laterally-arranged propelling baffle members curved concavely from above secured to the outer surfaces of said baffle plates.
13. An air lift assembly for use in flotation apparatus of the character described, comprising spaced substantially parallel air header side plates, a bottom closure secured to said side plates adjacent the bottom thereof, end closures secured to said side plates at each end thereof and projecting laterally a substantial distance beyond the outer surfaces of said side plates, baffle plates secured to said end closures adjacent their outer edges and supported thereby in spaced, substantially parallel relation with said side plates, said side plates at their upper edge portions being curved outwardly over and downwardly beyond said baffle plates, and a cover secured to said side plates adjacent their upper curved edges.
